UNITED STATES PATENT OFFICE.

FREDERICK S. GLINES, OF LYNN, MASSACHUSETTS, ASSIGNOR TO LORENZ MUTHER, OF NEWTON, MASSACHUSETTS.

FOLDING MACHINE.

Application filed October 23, 1922. Serial No. 596,308.

This invention relates to folding machines but is more especially designed with reference to machines for folding a binding tape around the edge of sheet material.

In the manufacture of shoes, it has been customary to provide certain styles with what is known as "cord" binding. This is accomplished by stitching a piece of tape or suitable fabric to the right side of the shoe part or material to be bound at its edge, then by turning the binding in a reverse direction over the stitching and around the edge of the material and by pressing the free edge of the binding material down upon the reverse side of the shoe part or other material; the engaging surfaces having previously been treated with cement. Since the binding material is turned in a reverse direction, the stitching is concealed and when the binding is turned tightly and smoothly around the edge of the material to be bound, a finished and attractive cord edge is presented. It is essential in this work that the binding material be turned tightly and smoothly about the edge of the bound material, otherwise the binding becomes loose and wrinkled when subjected to wear and destroys the attractive appearance of the shoes.

The main object of this invention is the provision of a machine adapted for this work which contains the minimum number of operating instrumentalities, and which is of simple construction and operation and yet efficient.

A further object is the provision of a gauge so constructed that it guides the material through the machine by contact with the outside surface of the upturned binding.

Another object of the invention is the provision of a gauge so constructed that it may be utilized for wiping the binding upwardly around the edge of the material to be bound previous to the turning operation.

Other objects of the invention will be more specifically set forth and described hereinafter.

One of the important features of my invention resides in the provision of a gauge substantially perpendicular in its operative portion to the work-support of the machine and extending below it which is adapted to guide the material by engagement with the

outside face of the binding. In this case the material is held against the gauge with the binding upturned around its edge and between the edge of the material and the gauge. This permits of the use of an unyielding gauge which maintains its position and yet does not interfere with the feeding of the work which is a distinct advantage. When work of this character is guided by means of a gauge adapted to engage the edge of the material to be bound above the binding, there is a tendency for the work to catch or to drag on the end of the gauge thereby causing defective work. By having the binding upturned around the edge of the material when it is held against the gauge, I am enabled to set my gauge nearer the turning member or plow and the binding is in a position which facilitates its turning by the plow without subjecting its edge to strain.

Another important feature of my invention consists in combining the gauge with the pressing member and in providing it with serrations or teeth so that it may be utilized for wiping the binding closely upwardly around the edge of the material as it is held against the gauge. It is very essential in applying binding that it be drawn tightly around the edge of the material, otherwise it will vary in thickness and become loose and flabby in use.

In the drawings illustrating the preferred embodiment of my invention, Figure 1 is an end elevation of a portion of a folding machine having my invention embodied therein; Fig. 2 is a side elevation of the same as viewed from the operator's seat; Fig. 3 is a view in perspective on an enlarged scale of a combined pressing member, gauge and wiper constructed in accordance with my invention; Fig. 4 is a bottom plan view of the same and Fig. 5 is a side elevation on an enlarged scale of the serrated or toothed portion of the gauge.

In the drawings my invention is shown as applied to a folding machine of the general type illustrated and described in United States Letters Patent No. 1,294,919, issued to William F. Lautenschlager, February 18, 1919. The operative end only of the machine is shown since the actuating mechanisms for giving such folding instrumentalities, as are retained, their appropriate

movements are the same as shown in said patent and operate in the same manner.

Referring to the drawings, 15 indicates the end of the lower arm, and 16 the end of the upper arm of the frame of the machine, 19 the lift-shaft, 20 the feed-bar and 21 an idler roll. The feed-bar is mounted in a housing 22, carried by a clamp-bearing 23 and the forward and backward movement is 10 imparted to the feed-foot 24 by the rocking of the housing 22. An arm 25, fixed on the end of the lift-shaft 19, is connected by a link 26 to a stud 27 carried by a split collar 28 secured to the upper end of the feed-bar 20, and the rocking of the lift-shaft 19 through these means imparts an up and down movement to the feed-bar 20 in the housing 22. The feed-bar is held in a lowermost position by a spring 30, and the 15 idler roll with which the feed-foot co-operates in the feeding movement is loosely mounted upon a screw stud 32 set in the end of the lower arm.

Through the foregoing, the feed-foot is 25 given a four-motion feed. In its forward movement (away from the operator) it is in a lowermost position, co-operating with the idler roll to feed the material forward in the machine. At the end of the feeding movement, the rocking of the lift-shaft 19, 30 through the medium of the arm 25, link 26 and collar 28, lifts the feed-bar 20 and feed-foot 24 to release the material and holds them in a raised position during their movement backward at the end of which they are 35 dropped into initial position. The material is therefore fed in a step-by-step manner. All of the foregoing construction and mode of operation is fully shown and described in 40 said Lautenschlager patent to which reference may be had.

Upon the end of the lower arm 15 is mounted a work-support 50 having a bevelled edge 51 toward the operator upon 45 which may be arranged, if desired, means for wiping over or straightening out the binding in a direction away from the material to be bound as the work is fed through the machine. The wiper shown is in the 50 form of a thin plate 53 having a portion 54 bent under the bevelled portion 51 of the work plate and is provided with a turned-up slightly hooked-over thin edge 55; this edge being oblique to the normal line of 55 feed. As the material is fed through the machine, the sharp edge 55 engages the binding and since that edge runs obliquely from left to right in the direction of the normal feed, its effect is to draw the binding away 60 from the material to which it is secured and thereby straighten it out.

For turning the binding over and downwardly toward the reverse side of the material a plow or turner 58 of ordinary form 65 may be mounted upon the work-support 50.

Preferably it is secured to or made integral with a flexible strip 91, counter-sunk in the work-support 50, and held in adjusted position by a screw 92. This arrangement permits the plow to yield slightly whenever a 70 thickened portion of the work passes under its nose and thereby prevents any dragging or straining of the material.

For pressing down the turned-over tape upon the reverse side of the material to be 75 bound, a presser-arm 60 carrying a presser 62 substantially L-shaped in plan but having the under surface cut away slightly at 80 63, is either made integral with or fixedly mounted on a lever 65 secured thereto by a screw 66 and held against rotation thereon by a pin 67. The lever 65 is provided with a shaft 68 mounted in the bearing 70 formed on the upper arm 16 and is arranged to oscillate therein.

Secured in the perpendicular portion of the lever 65 is a threaded screw 72 having a check nut 73, and provided with a longitudinal hole in its end in which is mounted a spiral spring 75. This spring bears against 90 a block 76, set in an arm 77, fixedly mounted on the end of the lift-shaft 19. Through the medium of these parts, the lever 65 is rocked by the oscillation of the lift-shaft 19 to raise and lower the presser arm and presser member, and the machine is so timed that the presser member is down between the feeding movements and elevated during the feeding movements. To hold the lever 65 in the position shown in Fig. 1 with the spring 75 95 abutting the block 76, a spring 80 set in a hollow screw 81 bears against the upper portion of the lever 65. The screw is threaded through an arm 83 forming a part of the upper arm 16 of the machine, and the pressure 100 exerted upon the lever 65 by the spring 80 105 may be adjusted by turning the screw one way or the other.

The foregoing construction constitutes no 110 part of the present invention. The stationary wiping device and the pressing member are shown and described in an application for Letters Patent filed by me jointly with Lorenz Muther in the United States Patent Office on July 24, 1922, Serial No. 576,965, 115 and the resilient plow or turner is the subject of another application to be filed by me.

The novel features of the present invention reside in the provision of a new form of gauge and of means for wiping the binding upwardly around the edge of the material. Preferably, in the application of my invention to the folding machine shown, the gauge and wiper are combined with the 120 pressing member but it is to be understood that in the application of my invention to other forms of folding machines, it may be preferable to make said members separate and independent.

In combining the gauge and wiper with 125

the pressing member; the presser-arm 60 may be provided with a bifurcation 88 which extends rearwardly toward the operator and then downwardly below the lower face of the presser 62 through a suitable opening in the work-plate 50; the bifurcation 88 being so formed that it is substantially perpendicular to the work-support at and just above the surface thereof, and is sufficiently long so that it extends below the work-plate at all times. On that portion of the face adapted to engage the work, the gauge 88 may be provided with serrations or teeth 90 (see Fig. 5) so faced as to catch the binding on the upward movement only and to slide over it on the downward movement.

The operation of the machine is as follows: The material is presented to the machine with the right side downward and with the binding turned over the stitching in a reverse direction and extending outwardly from the material and is inserted between the feed-foot and the idler roll, the feed-foot being in its initial position ready for feeding. In this initial position the work is held tightly against the gauge 88, the tape at that point being turned upwardly around the edge of the material to be bound, and in engagement with the gauge. The machine is then started. The feeding mechanism feeds the material one step, the edge of the work sliding by the gauge with the binding at that point in an upright position. During this feeding movement the work should be held firmly against the gauge in order that the binding by the gauge may be held tightly against the edge of the material. As the work is fed forward under the nose of the plow or turner, the binding is turned downwardly toward the reverse side of the material and at the end of the feeding movement the pressing member descends and presses the turned-over binding down upon the cemented reverse side of the material. As the pressing member descends the gauge 88 moves downwardly sliding by the work in engagement therewith. The pressing member remains in pressing position while the feeding means are returning to initial position and just before the next feeding movement the presser and gauge are raised and the teeth 90 on the gauge catch upon the upstanding binding at that point and draw it upwardly tightly around the edge of the material.

The work is thus fed through the machine in a step-by-step manner, the binding being wiped upwardly by the upward movement of the gauge while the work is held stationary by the feed foot. This action takes place as the presser member is raised from the work just after the feed-foot has come down upon the work to start the feeding movement. The wiping may be facilitated by holding the work in tight en-

gagement with the gauge, in which case the binding is drawn tightly around the edge of the material.

The advantages of a gauge of the character herein shown and described are manifold. It does not interfere with the turning of the binding material tightly around the edge of the material to be bound nor with the natural curve of the edge of the binding material given by the plow or turning device, since the gauge is outside of the binding and guides the material through engagement with the upturned binding.

Since the plow or turning device operates to turn the binding downwardly toward the reverse side of the material and away from the gauge, it is possible to place the gauge in close proximity to the plow and thereby secure a close grouping of the folding instrumentalities which is so conducive to perfect work.

The use of a gauge having a point adapted for contact with the edge of the material above the binding interferes with the turning of the binding tightly upwardly and around the edge of the material at that point and consequently such a gauge must be located a sufficient distance away from the plow or turning device to permit the tape to turn over naturally without straining the edge. This prevents close grouping of the folding instrumentalities and the perfect work which is secured by such close grouping.

In addition, the close proximity of my gauge to the plow gives no opportunity for the binding to relax or withdraw from the edge of the material after it has been wiped upwardly by the gauge and before it is turned downwardly by the plow, in consequence of which a close tight fold is attained.

It is to be understood that my invention is not to be limited to the exact form or the exact application herein shown and described, since it may be embodied in other forms of construction and may be applied to other forms of folding machines all within the purview of the following claims.

What I claim is:—

1. In a folding machine, the combination of a work-support, means for feeding material having a binding tape attached to one edge thereof, means for turning said tape around the edge of said material and a bifurcated member; one of the branches of said bifurcated member being adapted to press the said turned-over tape down upon the body of said material and the other of said branches being adapted to serve as a gauge.

2. In a folding machine, the combination of a work-support, means for feeding material having a binding tape attached to one edge thereof, means for turning said tape

- around the edge of said material and a bifurcated member; one of the branches of said bifurcated member being adapted to press said turned-over tape down upon the body of said material and the other of said branches extending forwardly and downwardly below said work-support and being provided with teeth for wiping said tape upwardly around the edge of said material.
3. In a folding machine, the combination with means for feeding, in a step-by-step manner, material having a binding attached at one edge to the edge of said material of a pivotally mounted member provided with bifurcated means for wiping the binding upwardly around the edge of the material and for pressing the free edge of the binding upon the body portion of the material.
4. In a folding machine, the combination with means for feeding, in a step-by-step manner, material having a binding attached to the edge thereof of a reciprocating member adapted to act as a guide and provided with bifurcated means for wiping the binding over the edge of the material and for pressing the free edge of the binding upon the body portion of the material.
5. In a folding machine, the combination with means for feeding, in a step-by-step manner, material having a binding attached to the edge thereof of a pivotally mounted reciprocating member provided with bifurcated means for wiping the binding over the edge of the material and for pressing the free edge of the binding upon the body portion of the material; said wiping means serving also to guide the material as it is fed through the machine.
6. In a folding machine, the combination of means for feeding in a step-by-step man-
- ner material having a binding attached to one edge thereof, means for turning said binding upwardly around the edge of said material and a pivotally mounted bifurcated member; one of the branches of said bifurcated member being adapted to serve as guiding means for the material and for wiping the binding upwardly around the edge of the material, and the other branch of said bifurcated member being turned at right angles for pressing the turned over binding down upon the body side of the material.
7. In a folding machine, the combination of a work-support, means for feeding material having a binding attached to one edge thereof, a plow for turning said binding down upon the reverse side of said material and means for pressing said binding to said reverse side; said pressing means being provided with an extension projecting at all times down below the surface of said work-support, said extension being provided with serrations for wiping the binding upwardly around the edge of said material before it is turned over by said plow.
8. In a folding machine, the combination of means for feeding material having a binding attached to one edge thereof, means for turning said binding down upon the reverse side of said material and means for pressing said binding to said material; said pressing means being provided with an extension projecting toward the front of the machine and downwardly below the work, said extension serving as a guide for the work and for wiping the binding up around the edge of the work.

In witness whereof, I hereunto set my hand this 20th day of October, 1922.

FREDERICK S. GLINES.
